Application February 10, 1950, Serial No. 143,440

14 Claims. (Cl. 187—29)

1

My invention relates to electro-mechanical automatic elevator controls, and its objects are to provide an elevator system wherein the selector control is predominantly mechanical and electrical connections are largely dispensed with or rendered less complex; to provide a more efficient control for causing the elevator car automatically to stop to discharge passengers at floors selected by the operator; to cause the elevator car, while travelling up or down, automatically to stop at any floor to pick up passengers desiring to travel in the direction in which the car is proceeding and later to return in the opposite direction to pick up passengers wishing to proceed in said reversed direction; to cause the car to stop to pick up passengers desiring to go in an opposite direction to that in which the car has been proceeding and then to proceed in such reversed direction if there are no passengers wishing to go in the original direction; to render the parts of the control and connections thereof accessible for inspection, adjustment, replacement, restoration and repair, and generally to provide an automatic elevator control which is simple and economical of construction, efficient in action, novel in design, and of prolonged life and durability. These and other objects will appear from the drawing and as hereinafter more particularly described and claimed.

Attention is hereby directed to the drawing, illustrating a preferred form of my invention, in which similar numerals of designation refer to similar parts throughout the several views, and in which:

Figure 1 is a simplified schematic representation of an elevator system, showing the application of my invention thereto;

Fig. 2 is a front elevation of the elevator car operating control mechanism;

Fig. 3 is a vertical section on line 3—3 of the control mechanism shown in Fig. 2, looking in the direction of the arrows;

Fig. 4 is a horizontal section on line 4—4, of Fig. 2, looking in the direction of the arrows;

Fig. 5 is an enlarged front elevation, partly in section, of the piloting head and adjacent parts shown in Fig. 2;

Fig. 6 is a horizontal section on line 6—6 of Fig. 5, looking in the direction of the arrows;

Fig. 7 is an enlarged detailed view of a portion of Fig. 5, showing the operation of the piloting head in effecting contact with a piloting switch;

Fig. 8 is a vertical section on line 8—8 of Fig. 7, looking in the direction of the arrows;

Fig. 9 is an enlarged detailed view of a part of

2

Fig. 5, showing in elevation the left end portion of the piloting head;

Fig. 10 is a rear elevation of one of the two multiple stop arms, pivotally mounted upon the backs of the ends of the piloting head, the contacting piloting switch being indicated in dashed lines;

Fig. 11 is a horizontal section on line 11—11 of Fig. 10, looking in the direction of the arrows;

Fig. 12 is a schematic wiring diagram showing generally the elevator control circuit;

Fig. 13 is a wiring diagram of a portion of the elevator run circuit; and

Fig. 14 is a key representation of the coils and contact members shown schematically in Fig. 12.

Referring to the drawing, I have illustrated in Figure 1 the main features of an assembly or system in which is incorporated the improvement constituting my invention, and which includes a conventional form of elevator hoistway 14 extending vertically through the building 15, and opening into the floors thereof (here shown to be three in number, but which may be any number desired). Conventionally suspended to slide vertically within said hoistway 14 through the employment of the usual cables 16, traction sheaves 17, and counter weights (not shown) driven by the hoisting motor 18, is the elevator car 19; the hoisting motor being operated through conventional switches mounted upon a relay panel piloted by my electro-mechanical automatic control mechanism 20. As shown, this mechanism 20 is connected to be driven by the well known means of two steel cables 21 and 22 attached to the car 19; one of which cables extends from the top of the car to be wound around an overhead sheave in the manner similar to a measuring tape, and the other cable extends from the bottom of the car around a tension sleeve and then upward to a second overhead sheave upon which it is similarly but oppositely wound. The overhead sheaves through the connection of sprockets and sprocket chain as hereinafter described cause the operation of the control mechanism 20, one cable winding up as the other is unwound in the driving operation. The usual up and down push buttons 19a and 19b are provided for causing the control mechanism to stop the car at the floor desired. These buttons allow a passenger outside the car to direct its passage to the floor from which the signal is given, and upon gaining admittance to the car, through the use of its push buttons thereafter to direct its progress to arrive

at the floor of his exit.

Reference may now be had to Figs. 2 to 11, inclusive, in which I have illustrated in detail the various parts of my improved electro-mechanical control mechanism 29, preferably housed within the long open frame 23 formed with square or rectangular top and bottom plates 24 and 25, secured at their corners to the elongated upright angle irons 26, 27, 28 and 29. In the center of the bottom plate 25 is formed the ball thrust bearing 30, in which is journalled against longitudinal movement the lower end of the upright screw 31, carrying the bevel gear 32 meshing with the bevel gear 33 upon the inner end of the operating shaft 34, which is horizontally disposed and journalled against longitudinal movement in the bearing 35 10 15 against the lower face of the plate 25. Upon the outer end of the shaft 34 is mounted the sprocket 36 connected by a sprocket chain 37 with the sprocket 38 mounted to rotate upon the horizontally disposed shaft 39 carrying the overhead sheaves 40. As will be observed, the bottom plate 25 is located well above the lower ends or feet of the said angle irons in order that sufficient clearance may be provided for the operation of the bevel gears 32 and 33 within the frame 23. The 20 25 top end of the upright screw 31 is journalled in the bearing 41 located in the center of the top plate 24.

Threaded to engage with the threaded portion 42 of the screw 31 is the sleeve 43 press fitted within the hub 44 of the deck platform 45a of the cross head 45, so that upon rotation of the shaft 31, the head 45 will be caused to travel up or down in accordance with the rotation of said shaft, and in co-ordination with the up and down motion of the elevator car in the manner well understood in the art; guide rods 46, 47 vertically extending between and secured to the plates 24 and 25 of the frame 23 and positioned to make sliding contact with the apertured ears 48 and 48a welded to the sides of the deck platform of said head, serving to keep and maintain said head without deviation in a straight path parallel to the upright angle irons of said box 26.

The main supporting body of the cross head 45 is a horizontally disposed square or rectangular metallic plate forming said deck platform 45a, upon which is mounted the piloting head 49, comprising the upright base or back plate 50; spaced top and bottom way strips 51 and 52 horizontally secured to said plate and forming the straight guideway 53 of uniform width between said strips; a main slide 54 and in sliding contact with the face thereof, the auxiliary slides 55 and 56, all located within said guideway and adapted separately to slide therein in sliding contact with the strips 51 and 52; transfer solenoids 57 and 58 secured to the rear face of the back plate 50; cams 59 and 60 welded to or integral with said main slide 54 and extending forwardly from the face thereof; auxiliary slide actuators 61 and 62 pivotally mounted upon pins 61a and 62a affixed to the top way strip 51; a tension spring 63 yielding connecting said auxiliary slides; stop arms 64 and 65 pivotally mounted upon the main slide 54 at the rear thereof; front plate 66 and upright directional tracks, consisting of the elongated up-tracks 67a and 67b, and the elongated down-tracks 68a and 68b, mounted upon the sides of the electrically nonconducting frame 83, secured to and carried upon the face of said front plate 66; the up-tracks being insulated electrically from the down-tracks by the insulation blocks 95 and 96 positioned therebetween and secured to said plate, and both up-tracks and down-tracks 75

being insulated from the piloting head by the frame 69.

Extending through the back plate 50 is the rectangular opening 70, through which extends and laterally slides the arm 71 welded to the rear face of the main slide 54, and upon the free end 71a of which arm is mounted the double armature 72, whose ends reciprocate within the coils 73 and 74 of the solenoids 57 and 58; the arrangement being such that the energization of one solenoid contemporaneously with the de-energization of the other will cause the main slide to move laterally to the right or left accordingly in the manner and for the purpose hereinafter described.

As shown more particularly in Figs. 6, 7 and 8, the main slide 54 is rectangular in form and is disposed to slide within the guideway 53, with its back in sliding contact with the front face of the back plate 50, and its top and bottom sides in sliding contact with the walls of the adjacent way strips 51 and 52. Also the face of the main slide 54 is in sliding contact with the backs of the auxiliary slides 55 and 56, the top and bottom sides of each of which are also in sliding contact with said way strip adjacent walls; the said slides 55 and 56 and the main slide 54 being kept in their said relative positions within the guideway 53 by the front plate 66 firmly secured to the front faces of said way strips. Secured to or integral with the main slide 54 are the cams 70 and 71; the cam 70 projecting from the top right end of said slide 54, and the cam 71 projecting from the bottom left end of said slide 54, the office of which cams is shortly to be described.

As shown in Figs. 5, 6 and 7, the auxiliary slides 55 and 56 have extending therethrough the rectangular openings 55a and 56a, through which extend and within which laterally slide the cams 59 and 60 respectively. Also affixed to the slides 55 and 56 are the outwardly projecting pins 55b and 56b, connected by the tension spring 63. Formed within the front plate 66, are the large recessed square or rectangular openings 66a and 66b, through which extend the cams 59 and 60, the pins 55b and 56b, and the pivotal mountings and associated moving parts of the auxiliary slide actuators 61 and 62.

Two duplicate stop arms 64 are attached to opposite ends of the main slide 54, in inverted relation one with the other, one of which is more particularly illustrated in Fig. 10, and which is shown to be pivotally mounted upon the elongated member 64a, that is vertically secured to the rear face of the left end of the main slide 54. Affixed to the arm 64, intermediate the ends thereof, is the block 72 of insulation material, and secured to one side of said block is the resilient upwardly extending contact finger 73, positioned to make spring contact with the fixed contact 74, mounted upon the block 75 of insulation material, which block is secured to the upper end of the member 64a.

Mounted one over the other in spaced relation upon the angle irons 26 and 27, are two sets of piloting switches, one set of which comprises the down pivoting switches 26a, 26b, 26c, 26d and 26e, affixed to angle iron 26, and the other set of which comprises the up pivoting switches 27a, 27b, 27c, 27d and 27e, affixed to angle iron 27; the said switches being arranged, switch 27a for the top floor and switch 26e for the bottom floor, and one of each set for each intermediate floor and all of said switches be-

ing electrically connected to call buttons and operated as hereinafter set forth. All of these piloting switches are of similar construction, except as adapted for the right or down side or the left or up side of the piloting head. Accordingly but one of these switches, as illustrated in Figs. 5, 6 and 7 as an example, will now be described. Such switch, as shown, is mounted upon an angle bracket 76 firmly affixed to the angle iron 26, and comprises, the support 77 secured to said bracket 76; the magnetic structure 78 and the coil 79 mounted upon said support; an outwardly extending pin 80 secured to the upper corner of the bracket 76, and pivotally mounted upon the said pin the armature 81, having the downward extension 82; a closed ended tubular brushholder 83, and telescoping therewith a brush 84, normally thrust forward by the compression spring 85 within said holder and bearing against the closed end thereof, the telescoping movement of said brush being limited by the pin 86 carried thereon and engaging with the slot 87 in the wall of said holder; the post 88 secured to the bracket 76, the said post having formed therein the socket 89 shaped to receive the locking ball 90 resting upon the compression spring 91 seated within said socket, and the said ball being positioned to effect yielding locking engagement with the cup-like depressions 92 and 93 in the bottom of the extension 82 of the armature 81 upon movement thereof; and the roller 94 mounted upon the central portion of said extension and positioned to make sliding contact both with the cam 71 upon the end of the main slide and with the outer end of the adjacent auxiliary slide 56 as hereinafter set forth.

In Figs. 12, 13 and 14, I have shown schematically the wiring connections of my improved electro-mechanical elevator control. Here the leads extending from one side of each of the the up and down buttons 19a and 19b are shown to be connected with the common feed L₂, and the other side of each of said buttons is shown to be connected with one side of the pilot switch coils A, B, C, D, E and F upon the corresponding piloting switches; the other side of said coils being connected with the common feed L₁. Also connected to said common feed L₁ are the brushes 84 of the down piloting switches 26a to 26e, shown in the control circuit of Fig. 12 as D', E' and F', and the up piloting switches 27a to 27e, shown in said circuit as A', B' and C', and arranged to make sliding contact with either the up or down directional tracks as hereinafter described. As shown, the up directional tracks 67a and 67b are connected by lead 95 to one side of a normally closed interlock 96a on the down directional switch; the other side of said interlock being connected by lead 97 to one side of the coil 98 of the up directional switch and the other side of said coil being connected by lead 99 with the common feed L₂. Similarly the down directional tracks 68a and 68b are connected by lead 100 to one side of a normally closed interlock 98a on the up directional switch, the other side of said interlock being connected by lead 101 to one side of the coil 96 of the down directional switch, and the other side of said coil being connected by lead 102 with the common feed L₂.

Also connected with said common feed L₁ by lead 103 is one side of normally open interlock 98b on the up directional switch and one side of normally open interlock 96b on the down directional switch; the other side of interlock 98b

being connected by lead 104 to one side of the coil 105 of the up transfer solenoid, and the other side of interlock 96b being connected by lead 106 to one side of the coil 107 of the down transfer solenoid, and the remaining sides of said coils being connected by lead 108 to the feed L₂.

Connected with feed L₁ by lead 111, is one side of a pair of contacts 109a of the stop switch, the other side of said stop switch being connected by lead 112 with one side of the coil 110 of the start switch; the other side of coil 110 being connected by lead 113 to the common feed L₂. Also connected with feed L₁ by lead 114 is one side of the up multiple stop switch 64; the other side being connected by lead 115 to one side of the down multiple stop switch, and the other side of said down multiple stop switch being connected by lead 116 to one side of the coil 109 of the stop switch, and the other side of said coil 109 being connected by lead 117 to the common feed L₂.

In Fig. 13 is shown a special form of part of the elevator run circuit, in which, connected by lead 118 with the common feed L₃, is one side of a pair of contacts 110a on the start switch, and one side of a pair of contacts 109b on the stop switch; the other side of each of said switches last named being connected by lead 119 with one side of a pair of contacts 98c on the up directional switch, and with one side of a pair of contacts 96c on the down directional switch.

The operation of my invention may now be considered. When a call button is pushed, the corresponding piloting switch coil 79 is energized and the brush 84 is brought in slidable contact with one of the up directional tracks 67a or 67b, or one of the down directional tracks 68a or 68b. If the elevator is above the floor where the button is pushed, the brush will contact one of the down directional tracks. Conversely, if the elevator is below the said floor, the brush will contact one of the up directional tracks. As shown by the elevator control circuit diagram Fig. 12, this action will cause either the up directional switch coil 98, or the down directional switch coil 96 to be energized, depending upon whether an up or down directional track has been contacted. The up 98c or the down 96c directional switch contacts will then be closed causing the elevator to run in the desired direction.

It should be noted, as shown by Fig. 12, that if an up button is pressed, contacts 98b on the up directional switch will close, causing the up transfer solenoid coil 105 to be energized. The main slide 54 of the piloting head 49 will then be moved to the left or up side. Conversely, if a down button is pressed, contacts 96b will close, causing the down transfer solenoid coil 107 to be energized. The main slide 54 will then be moved to the right or down side.

Referring now to Figs. 5, 6 and 7, it will be observed that when the main slide 54 moves from the right side to the left side of the piloting head 49 due to the action of transfer solenoid 57, the cam 60 passes under and lifts roller 62b, which action causes auxiliary slide actuator 62 to rock upon pin 62a, and to push pin 56b to the right. Since pin 56b is affixed to auxiliary slide 56, said auxiliary slide will be moved to the right. As the cam 60 continues to move to the left, roller 62b will pass over the top of said cam and drop down. The auxiliary slide 56 will then be returned to its original position by the action of spring 63.

In a similar manner, if the main slide 54 moves

from the left side of the piloting head 49 to the right, due to the action of transfer solenoid 58, auxiliary slide 55 will be moved outward to the left and then return to its original position. It will further be observed that when the main slide is positioned to the right side of the piloting head, the cam 71 will be in a position such as to contact the roller 94 on a piloting switch on the right or down side of the mechanism, if said piloting switch has been energized so as to make contact between the brush 84 and one of the directional slides.

Once the elevator has started to run, it will continue to run until the brush which is in contact with one of the directional tracks slides upon one of the insulation blocks 95 or 96.

Let it be assumed that an up button at the third floor has been pushed and that the elevator is at the first floor. The coil 79 of the piloting switch corresponding to the third floor on the left or up side of the mechanism will thereupon be energized, pulling armature 81 down and moving brush 84 outwardly to contact the up directional slide 67a. As already explained, this will cause the elevator to run in an upward direction. Since the piloting head at all times moves in step with the elevator, it will also move upwardly. The up directional track will therefore slide past the brush 84 until said brush slides upon the insulation block 95. When this occurs, the circuit will be broken and the up directional switch contact 99b will open, causing the elevator to stop. Now, if the elevator continues in an up direction, the cam 79 will contact the roller 94 and move the brush 84 back away from the insulated block 95. This action cancels that call. If, however, the elevator goes down from the third floor, the main slide 54 will transfer to the right side of the piloting head as already described. The auxiliary slide 55 will then contact roller 94 and move the brush 84 back, thus canceling the call.

If a down button at the third floor had been pushed, the coil 79 of the piloting switch corresponding to the third floor and on the right or down side of the mechanism would have been energized. The brush 84 would then contact the up directional slide 67b, and again cause the elevator to run in an up direction to the third floor.

As the elevator starts down from the third floor, the main slide 54 transfers to the right as already described, bringing cam 71 in position to contact the roller 94 and push the brush 84 back canceling the call.

Let there now be considered the case where two or more call buttons have been pushed. Let it be assumed that up buttons at the second and third floors have been pushed. There will then be two brushes contacting the up directional track 67a. As the elevator approaches the second floor, the brush of the corresponding piloting switch will slide upon the insulating block 95. This action alone, however, will not cause the elevator to stop, since the up directional switch coil 99 is still energized due to the fact that there is still a brush contacting the up directional slide 67a. As before mentioned brush slides upon the insulating block 95, the pivotally mounted arm 64 contacts the roller 94 of the second floor up piloting switch. This action moves contact 73 away from contact 74. Referring now to Figs. 12 and 13 the up multiple stop switch 64 is opened, stop switch coil 109 is de-energized and stop switch contacts 109b open. The circuit to the up directional switch contacts 98c is thereupon opened and the elevator

will stop. When stop switch coil 109 is deenergized, contacts 109a close, causing start switch coil 110 to be energized. Start switch contacts 110a in accordance with timing mechanism there-in incorporated, then close after a controlled interval of time has elapsed. The circuit to the up directional switch 98c is thereupon reestablished, causing the elevator to continue in an upward direction to answer the call at the third floor.

As the elevator moves away from the second floor, the piloting head 49 moves away from the second floor up piloting switch. The pivotally mounted arm 64 on the left end of the main slide thereby is caused to move past roller 94, allowing contact 73 again to close with contact 74. The stop switch coil 109 is then reenergized, causing stop switch contacts 109b to reclose and contacts 109a to open. When contacts 109a open, start switch coil 110 is deenergized and start switch contacts 110a open. The run circuit is now reestablished in preparation for the next floor stop. It should be noted that here the elevator has traveled in an upward direction to make up calls, and that it has stopped consecutively at each floor where up buttons have been pressed as the car came to said floors.

Let it now be assumed that down buttons instead of up buttons had been pressed at the second and third floors. There would then be two brushes contacting the up directional track 67b; said brushes being mounted on piloting switches corresponding to the second and third floors and being on the right or down side of the machine. As already explained, the main slide 54 will be positioned to the left or up side of the mechanism. Therefore, as the piloting head moves upwardly the pivotally mounted arm 64 on the right end of the main slide 54 will not be in position to contact rollers 94 on the down piloting switches at the second and third floors. Under these conditions, the elevator will not stop at the second floor but will continue to run in an upward direction until the highest brush (in this case the brush corresponding to the third floor) slides upon the insulating block 95. The elevator will then stop due to the fact that no brushes are contacting the up directional track 67b. After a timed interval the down directional switch coil 96 will be energized, since the brush 84 on the down piloting switch corresponding to the second floor has passed from the up directional track 67a to the down directional track 68b. The down directional switch contacts 96c will then close and the elevator will run in a down direction to the second floor. It should be noted that when the piloting head is moving in a down direction, the main slide 54 will be to the right or down side of the piloting head 49. The pivotally mounted arm 64 on the right or down end of the main slide is then in position to contact rollers 94 of the piloting switches on the right or down side of the mechanism, where said arm will function to stop the car in the down direction when more than one brush is contacting the down directional track 68b. Calls are canceled as already described.

My invention may be embodied in other specific forms without departing from the spirit or essential characteristics thereof. The present embodiments, as above set forth are therefore to be considered in all respects as illustrative and not restrictive, the scope of my invention being indicated by the appended claims rather than by the foregoing description, and all changes which may come within the meaning and range of equival-

ency of the claims are therefore intended to be embraced therein.

What I claim and desire to secure by Letters Patent is:

1. In a control system for an elevator car adapted for starting and stopping the car, said system comprising electrically set piloting and mechanically reset piloting switches and two pairs of directional tracks with insulating blocks interposed therebetween for starting and stopping the car, and selector control mechanism responsive to said switches.

2. In a control system for an elevator car adapted for starting and stopping the car, said system comprising electrically set and mechanically reset piloting switches and two pairs of directional tracks with insulating blocks interposed therebetween, a piloting head secured to said tracks, and duplicate stop arms in inverted relation one with the other mounted upon said piloting head, and positioned to initiate the stopping of the car.

3. A control system for an elevator car, including a plurality of piloting switches and a piloting head, said system comprising means for electrically actuating and setting up said switches for starting the car, means for mechanically holding said switches in starting and running position, and means for mechanically resetting said switches by action of said piloting head.

4. A control system for an elevator car, including a plurality of piloting switches and a piloting head, said system comprising means for electrically actuating and setting up said switches for starting the car, means for mechanically holding said switches in starting and running position, and main slide means for mechanically resetting said switches by action of said piloting head.

5. A control system for an elevator car, including a plurality of piloting switches and a piloting head, said system comprising means for electrically actuating and setting up said switches for starting the car, means for mechanically holding said switches in starting and running position, and retractable cam means for mechanically resetting said switches by action of said piloting head.

6. A control system for an elevator car, including a plurality of piloting switches and a piloting head, said system comprising means for electrically actuating and setting up said switches for starting the car, means for mechanically holding said switches in starting and running position, retractable cam means and main slide means for mechanically resetting said switches by action of said piloting head.

7. A control system for an elevator car, including a plurality of piloting switches and a piloting head, said system comprising means for electrically actuating and setting up said switches for starting the car, means for mechanically holding said switches in starting and running position, and multiple slide means for mechanically resetting said switches by action of the piloting head.

8. A control system for an elevator car, including a plurality of piloting switches and a piloting head, said system comprising means for electrically actuating and setting up said switches for starting the car, means for mechanically holding said switches in starting and running position, and retractable cam and multiple slide means for mechanically resetting said switches by action of the piloting head.

9. A control system for an elevator car, including a plurality of piloting switches and a piloting head, said system comprising means for electrically actuating and setting up said switches for starting the car, means for mechanically holding said switches in starting and running position, and retractable cam means and main and multiple slide means for mechanically resetting said switches by action of the piloting head.

10. A control system for an elevator car, including a plurality of piloting switches and a piloting head, said system comprising means for electrically actuating and setting up said switches for starting the car, means for mechanically holding said switches in starting and running position, and retractable cam means and main means and auxiliary multiple means for mechanically resetting said switches by action of the piloting head.

11. A control system for an elevator car, including a plurality of piloting switches and a piloting head, said system comprising means for electrically actuating and setting up said switches for starting the car, means for mechanically holding said switches in starting and running position, and retractable cam means and main and auxiliary multiple slide means for mechanically resetting said switches by action of the piloting head.

12. A control system for an elevator car, including a plurality of piloting switches and a piloting head, said system comprising means for electrically actuating and setting up said switches for starting the car, means for mechanically holding said switches in starting and running position, and retractable cam means and main and auxiliary multiple slide means and auxiliary slide actuators for mechanically resetting said switches by action of the piloting head.

13. A control system for an elevator car, including a plurality of piloting switches and a piloting head, said system comprising means for electrically actuating and setting up said switches for starting the car, means for holding said switches in starting and running position, and retractable cam means and main and auxiliary multiple slide means and auxiliary slide actuators for mechanically resetting said switches by action of the piloting head, as the elevator car after a stop has been made continues in the same running direction.

14. A control system for an elevator car, including a plurality of piloting switches and a piloting head, said system comprising means for electrically actuating and setting up said switches for starting the car, means for holding said switches in starting and running position, and retractable cam means and main and auxiliary multiple slide means and auxiliary slide actuators for mechanically resetting said switches by action of the piloting head, as the elevator car after a stop has been made moves away from a floor in a direction opposite to that in which said car was running before making said stop.
